CLAIM

I claim the ornamental design for sealing clips, as shown and described.

DESCRIPTION

FIG. 1 is a perspective view of sealing clips showing my new design;

FIG. 2 is a right end view thereof;

FIG. 3 is a top plan view thereof;

FIG. 4 is a bottom plan view thereof;

FIG. 5 is a side elevational view thereof;

FIG. 6 is a side elevational view of an alternative configuration thereof, wherein the inner sealing clip is slidably withdrawn from within the outer sealing clip; and,

FIG. 7 is a perspective view of a sealing clip, shown separately for ease of disclosure.

The broken lines showing a third sealing clip are for illustrative purpose only and forms no part of the claim design.
